CLAIM

The ornamental design for a playing card, as shown and described.

DESCRIPTION

FIG. 1 is a front view of a playing card showing my new design;

FIG. 2 is a front view of an embodiment of the playing card; and,

FIG. 3 is a front view of an embodiment of the playing card. Rear, side, top, and bottom views are not claimed. The broken lines in FIGS. 2 and 3 form portions of the playing card forming no part of the claimed design.

1 Claim, 3 Drawing Sheets

FIG. 1

FIG. 3
